US00D571219S

(12) **United States Design Patent** (10) **Patent No.:** **US D571,219 S**
(45) **Date of Patent:** **** Jun. 17, 2008**

(54) **COSMETIC BOTTLE**

(75) Inventor: **Kimberly J. McCoy**, Milford, CT (US)

(73) Assignee: **ELC MANAGEMENT LLC**, New York, NY (US)

(**) Term: **14 Years**

(21) Appl. No.: **29/296,908**

(22) Filed: **Oct. 31, 2007**

(51) **LOC (8) Cl.** **09-01**

(52) **U.S. Cl.** **D9/546**; D9/544

(58) **Field of Classification Search** D9/516, D9/517, 529, 559, 560, 562, 564, 574, 575, D9/453, 537-539, 544, 545, 546, 500, 501, D9/503, 504, 505, 548, 549, 692, 688, 690, D9/691; D24/110, 119, 232; D28/91.1, D28/76

See application file for complete search history.

(57) **CLAIM**

The ornamental design for a cosmetic bottle, substantially as shown and described.

DESCRIPTION

FIG. 1 is a perspective view of a cosmetic bottle showing my new design;

FIG. 2 is an exploded perspective view thereof, showing the cap separated from the bottle;

FIG. 3 is a side elevational view thereof, the other side, front and rear elevation views being identical thereto;

FIG. 4 is a side elevational view thereof, with the cap removed;

FIG. 5 is a top plan view of the cap of the cosmetic bottle shown in FIG. 2;

FIG. 6 is a bottom plan view thereof;

FIG. 7 is an exploded side elevation view of the cosmetic bottle shown in FIG. 2;

FIG. 8 is an exploded side elevation view of the cosmetic bottle shown in FIG. 3, showing the cap and dropper separated from the bottle;

FIG. 9 is a side elevation view of the cap of the cosmetic bottle shown in FIG. 8;

FIG. 10 is a side elevation view of the dropper shown in FIG. 8;

FIG. 11 is a bottom plan view of the cosmetic bottle shown in FIG. 1;

FIG. 12 is a top plan view of the cosmetic bottle shown in FIG. 4;

FIG. 13 is a top plan view of the cosmetic bottle shown in FIG. 1;

FIG. 14 is a top plan view of the dropper assembly shown in FIG. 10; and,

FIG. 15 is a bottom plan view of the dropper assembly shown in FIG. 10.
